UNITED STATES PATENT OFFICE.

CHARLES T. CARNAHAN, OF DENVER, COLORADO.

HANDLE FOR PNEUMATIC HAMMERS.

No. 839,727.

Specification of Letters Patent.

Patented Dec. 25, 1906.

Application filed July 31, 1906. Serial No. 328,683.

To all whom it may concern:

Be it known that I, CHARLES T. CARNAHAN, a citizen of the United States, residing at Denver, in the county of Denver and State 5 of Colorado, have invented new and useful Improvements in Handles for Pneumatic Hammers, of which the following is a specification.

This invention relates to handles for pneumatic hammers, and aims to provide a handle in a manner, as hereinafter set forth, which will enable the rotating or turning of the cylinder of the hammer independently of the handle, and which will also permit of the 15 handle and cylinder being rotated or turned in unison.

Primarily the invention aims to improve the construction of pneumatic hammer set forth in application, Serial No. 280,194, filed 20 September 26, 1905; and to this end the invention consists in providing a hammer with a buffer for relieving the operator to a considerable extent of the jar and vibration when the hammer is operated.

25 The invention further aims to provide a hammer for pneumatic drills in a manner as hereinafter set forth which shall be simple in its construction, readily connected to the cylinder of the hammer, strong, durable, efficient in its use, comparatively inexpensive to manufacture, and embodying means to overcome the jar of the piston of the hammer.

With the foregoing and other objects in view the invention consists of the novel construction, combination, and arrangement of parts hereinafter more specifically described, and illustrated in the accompanying drawings, which form a part of this specification, and wherein is shown the preferred embodiment 35 of the invention; but it is to be understood that changes, variations, and modifications can be resorted to which come within the scope of the claims hereunto appended.

In the drawings, wherein like reference 45 characters denote corresponding parts throughout the several views, Figure 1 is a view, partly in vertical section, of a handle in accordance with this invention, also showing a portion of the cylinder of the hammer. 50 Fig. 2 is a side elevation; and Fig. 3 is a top plan, a portion of the grip being shown in dotted lines.

Referring to the drawings by reference

characters, 1 denotes the cylinder of the pneumatic hammer and which has mounted 55 upon one end thereof a cap 2, the latter being provided with screw-threads adapted to engage with screw-threads formed upon the periphery of the cylinder. Centrally of the upper face of the cap 2 a protuberance 3 is 60 provided which is exteriorly screw-threaded, and engaging the exterior screw-threads of the protuberance is an internally-screw-threaded retaining-sleeve 4, provided at its top with a laterally-extending annular flange 65 5. The retaining-sleeve 4 when secured in clamping position has its lower edge resting upon the upper face of the cap 2.

The reference character 6 denotes a grip, formed of a U-shaped bar of suitable material, terminating in a collar 7, the inner diameter thereof being such as to enable the said collar to surround the retaining-sleeve 4 when the latter is in operative position and, furthermore, to allow of the grip swiveling 75 upon said sleeve. When the grip 6 is in position, so that the collar 7 will surround the sleeve 4, the flange 5 connects the grip to the cap 2. Surrounding the sleeve 4 and arranged below the collar 7 is a washer 8, and 80 interposed between the washer 8 and the upper face of the cap 2 and surrounding the lower portion of the sleeve 4 is a resilient annular member 9, constituting a buffer or cushioning means to relieve the jar upon the 85 operator when using the hammer.

The grip is coupled to the cap, so that the grip cannot be rotated independently of the cap through the medium of a connecting-lever 10, which is pivoted between a pair of 90 ears 11, projecting laterally from the cap 2 and has bearing against its lower end the upper free end of a leaf-spring 12. This spring is fixedly connected at its lower end to the cap 2. The connecting-lever 10, when 95 moved to coupling position so as to couple the grip to the cap 2, is positioned between a pair of laterally-extending lugs 13, formed integral with the collar 7. By providing the connecting-lever 10 in a manner as stated it 100 is evident that when it is positioned between the lugs 13 the grip will be connected to the cap, so that the grip cannot be rotated independently of the cap; but when the lever 10 is moved to a position between the lugs 13 105 the grip will rotate in unison with the cap.

The function of the spring 12 is to retain the connecting-lever 10 in its lowered or inoperative position.

From the foregoing description, taken in connection with the accompanying drawings, it is evident that a handle for a pneumatic hammer is set up which will permit of the handle being rotated continuously and independently of the cylinder of the hammer, which will also enable the rotating of the handle and cylinder of the hammer continuously in unison, will provide a cushioning or buffer means to relieve the jar upon the operator, owing to the reciprocation of the piston of the hammer and which, furthermore, will enable the gripping element of the handle to be readily connected and disconnected from the cylinder or the cylinder-cap. Although the cylinder is shown as provided with a cap for one end thereof, said cap having a protuberance, yet the protuberance can be formed integral with the cylinder, as will be evident. During the operation of drilling it is essential that the tool be rotated or turned. This is usually accomplished in portable pneumatic hammers by the operator rotating or turning the entire device from the handle end thereof; but by the application of the means hereinbefore referred to it is not necessary for the operator to utilize more than one hand when rotating the tool. The other hand would press the handle and remain stationary. This is not the case when operating pneumatic hammers now in general use, for the reason that the left hand (or one hand) has to turn with the device when the device is being turned back and forth by the right hand (or the other hand); but it will be evident that by the application of the means hereinbefore set forth it is not necessary to utilize more than one hand when the device is rotated, that hand being the hand which grips the air-supply pipe or the cylinder, and, furthermore, by providing the pneumatic hammer with the means as hereinbefore set forth the operator can press his body against the handle of the device during the rotation thereof, thereby retaining the device in operative position and at the same time permitting of the operator's hands being free. The operator then, when occasion so requires, can turn the cylinder of the hammer independently of the handle at the same time that the operator's body is pressed against the handle which retains the device in operative position during the act of rotating or turning the cylinder. Furthermore, the interposition of the resilient or cushioning means between the collar of the grip and the top of the cylinder or cap prevents the operator from feeling the jar or vibration due to the operation of the hammer to any great extent.

Having thus fully described my invention, what I claim as new, and desire to secure by Letters Patent, is—

1. In a pneumatic hammer, the combination with the cylinder thereof having an exteriorly - screw - threaded protuberance extending from one end thereof, a grip terminating in a collar, and a sleeve engaging the screw-threads of the protuberance and provided with a flange engaging the collar for swivelly connecting the grip upon one end of the cylinder to enable the grip to be rotated independently of the cylinder: 75

2. In a pneumatic hammer, the combination with the cylinder thereof having an exteriorly - screw - threaded protuberance extending from one end thereof, a grip terminating in a collar, a sleeve engaging the screw-threads of the protuberance and provided with a flange engaging the collar for swivelly connecting the grip upon one end of the cylinder to enable the grip to be rotated independently of the cylinder, and a cushioning means interposed between the collar and that end of the cylinder from which the protuberance extends. 85

3. In a pneumatic hammer, the combination with the cylinder thereof having an exteriorly - screw - threaded protuberance extending from one end thereof, a grip terminating in a collar, a sleeve engaging the screw-threads of the protuberance and provided with a flange engaging the collar for swivelly connecting the grip upon one end of the cylinder to enable the grip to be rotated independent of the cylinder, a cushioning means interposed between the collar and that end of the cylinder from which the protuberance extends, and means carried by the cylinder for coupling the grip therewith so as to compel the rotating of the cylinder and the grip in unison. 100 105

4. In a pneumatic hammer, the combination with the cylinder thereof, of a grip swivelly connected upon one end of the cylinder thereby permitting of the cylinder rotating independently of the grip, a cushioning means interposed between the grip and the cylinder, and means carried by the cylinder for coupling the grip therewith so as to compel the rotating of the cylinder and the grip in unison. 110 115

5. In a pneumatic hammer, the combination with the cylinder and a grip thereof, of means for connecting the grip to one end of the cylinder to permit of the cylinder being rotated independently of the grip, a cushioning means interposed between the grip and the cylinder, and means for coupling the grip with the cylinder to compel the cylinder and grip to be rotated in unison. 120

6. In a pneumatic hammer, the combination with a closure-cap for one end of the cyl- 125

inder and a protuberance carried by said cap, a grip, means engaging the protuberance for swivelly connecting the grip upon the cap, a cushioning means interposed between the grip and the cap, and means for coupling the grip to the cap to prevent rotary movement of the grip upon the cap.

In testimony whereof I have hereunto set my hand in presence of two subscribing witnesses.

CHARLES T. CARNAHAN.
